UNITED STATES PATENT OFFICE.

ASAHEL TODD, OF PULTNEYVILLE, NEW YORK.

EXTENSION-LADDER.

SPECIFICATION forming part of Letters Patent No. 307,734, dated November 4, 1884.

Application filed April 30, 1884. (No model.)

To all whom it may concern:

Be it known that I, ASAHEL TODD, a citizen of the United States, residing at Pultneyville, in the county of Wayne and State of New York, have invented a new and useful Extension-Ladder of which the following is a specification.

My invention relates to improvements in extension-ladders, first, in the use of a compensating spiral spring to regulate the contraction and expansion of the ropes used in raising or lowering the upper section; second, a flexible spur pivoted to a counterbalance-hook to allow the upper section to be lowered without swinging the hook; third, an adjustable claw attached to the upper part of the lower section, to be used when required as a roof-ladder; fourth, an iron or wooden brace fastened to the sides of the lower section to strengthen and stiffen the lower section. I attain these objects by the use of the several parts illustrated in the accompanying drawings, making a part of this specification, in which—

Figure 1 is a perspective view of the ladder complete. Fig. 2 shows the position of the flexible spur when descending past the rounds of the lower section. Fig. 3 represents the spur detached, and the dotted line showing the position of the spur when the ladder is being extended or the hook fastened to a round of the lower section. Fig. 5 shows the manner of tightening the brace-rod. Fig. 4 is a toothed wheel and cap attached to the top of the upper section.

Like letters of reference refer to similar parts in the several figures.

To enable others to use my invention I will describe the manner of constructing the same.

The sides of the lower section, A A, Fig. 1, should be spread at the bottom to form a wide base, and from the bottom may contract to the lower clips, B B, where they must be parallel. The clips B B are made of heavy band-iron riveted to the inner side of the lower section, A A, and bent to conform to the width and thickness of the upper-section sides C C. In the center of the upper round of the lower section fasten the pulley n. The upper-section sides C C must be parallel and narrow enough to slide freely between the sides of the lower

section and to move easily under the curved ends of the clips B B. The cap K, Figs. 1, 5, and 6, is a piece of band-iron with a hole punched near one end, then turned over, forming a right angle, as shown in Fig. 5. A channel is cut in the sides of the lower section at the top and near the upper edge of the side A A. The cap is then fastened over the channel with the short angle over the end of the side A, as shown in Figs. 1 and 6. At a, Fig. 1, bore a hole; then pass through the hole the rod H, having on the inside end a head to prevent it from drawing through. Now bend the rod upward, passing the end under the cap K in the channel and through the hole punched in the cap. This end of the rod should have a thread cut to screw a nut down firmly upon the cap. The props b' b' should have a notch for the rod H to rest in, and should be thick enough to bend the rods outward, as shown in Fig. 1, and downward, even with the lower edge of A, as shown in Fig. 6. These props may be made of wood or iron and should be secured to the sides A near or over the rounds. The claw f', Figs. 1 and 6, is a piece of iron fastened at one end by a screw or rivet to the side A. When the lower section is used as a roof-ladder, the claw f' is turned against the stop g', forming a right angle with the ladder and conforming to the ridge and roof of the building. The hook E is made of cast-iron, curved and counterbalanced, so it will readily hook over a round of the lower section and retain the upper section in position, as represented in Fig. 1. The hook has a hole cast in the center large enough to allow it to swing easily upon the lower round of the upper section. The hook has a flexible spur, C, pivoted to the center of the hook, which prevents it from fastening to a round when descending, as shown. As the upper section is being raised, the curved back edge of the hook E alternately strikes the rounds of the lower section, and then gives backward by turning on its round, so as to pass by, its weighted end always causing the hook to resume its position. The spur C, being pivoted, also gives backward as it strikes against the rounds of the lower section, and after giving backward as far as it can causes the hook E to partially revolve, so as to allow

the spur to slip past. When the upper section has been raised high enough, the spur serves to guide the hook, so that it will catch over any desired round, and thus serve to assist in supporting the upper section in place, passing a round in Fig. 2. After passing a round, the spur falls to the position represented by the dotted line c' , Fig. 3.

I am aware that counterbalance-hooks for extension-ladders have been used with the spur cast solid with the hook; but hooks cast in one piece nearly revolve when descending, and are apt to strike the counter-balance d , Fig. 3, upon a round, thereby breaking the round or endangering the hook. The flexible spur, when passing rounds in descending, merely turns up to the hook, swinging the hook slightly.

The toothed wheel W , Figs. 1 and 4, is made of cast-iron, with an axle, upon which it revolves. The cap h' , Fig. 4, has a hole cast or punched suitable for the axle of the wheel W . Bore a hole near the top and lower edge of C , in it place one arm of the axle of the wheel W , and screw the cap h' over the other axle, as represented in Fig. 1. The wheels W should project below the edge of the sides CC , so the weight of the ladder will rest upon them when against a building.

J , Fig. 1, is a spiral spring securely fastened to the round of the upper section, as at L . The lower part of the spring should closely coil around the shank of the pulley m .

To adjust the ropes used in raising and lowering the upper section, lay the lower section upon benches with the clips B upward. Place the upper section on the rounds of the lower section and under the curved end of the clips B . Tie the rope e to the second round from the bottom of the upper section

at f'' , pass the free end of the rope between the rounds of the upper and lower sections, through the pulley m , and under the rounds of the lower section, bore a hole through the windlass D at g' , pass the rope through, and tie a knot. By turning the crank a' it will wind the rope around the windlass and extend the ladder to the extreme limit desired. Tie the second rope, b , to the round f of the upper section, pass the free end through the pulley n and between the rounds of the upper and lower sections to the windlass D , bore a hole at c'' , pass the rope through, and tie a knot.

The contraction or expansion of the ropes is equalized by the spiral spring J .

What I claim, and desire to secure by Letters Patent, is—

1. The combination, with the sliding sections of an extensible ladder, of the ropes b e , passing over the pulleys m n , attached to said sections, respectively, the pulley m being provided with a spring, J , substantially as shown. 60

2. The combination, with the sections of an extension-ladder and a mechanism for raising and lowering the upper section, of counterbalanced hooks upon the rounds of the upper section, and the pivoted spurs which are attached to the hooks, the said hooks being adapted to partially rotate upon the rounds of the ladder, substantially as described. 65

3. The combination of the adjustable claw f' with the sides A of the ladder, substantially as set forth.

4. The combination of the brace H and cap K with the pieces b' , substantially as specified. 75

ASAHEL TODD.
